UNITED STATES PATENT OFFICE.

JONAS NORTHRUP, OF HOPEDALE, MASSACHUSETTS, ASSIGNOR TO DRAPER COMPANY, OF HOPEDALE, MASSACHUSETTS. A CORPORATION OF MAINE.

TRAVERSE-MOTION FOR YARN-SPINNING APPARATUS.

No. 882,793.

Specification of Letters Patent. Patented March 24, 1908.

Application filed February 13, 1907. Serial No. 357,116.

To all whom it may concern:

Be it known that I, JONAS NORTHRUP, a citizen of the United States, and resident of Hopedale, county of Worcester, State of Massachusetts, have invented an Improvement in Traverse-Motions for Yarn-Spinning Apparatus, of which the following description, in connection with the accompanying drawing, is a specification, like letters on the drawing representing like parts.

This invention has for its object the production of a novel traverse motion particularly adapted for use in connection with yarn spinning apparatus, to impart to the 15 ring-rail a peculiar traverse, whereby the yarn is laid upon a yarn-receiver in an improved and efficient manner.

Several forms of spinning apparatus have been devised heretofore to form upon the 20 yarn-receiver or bobbin a preliminary winding or bunch, and thereafter a main or service winding, for subsequent use in the shuttles of automatic filling-replenishing feeler looms, wherein a feeler operates to effect a change 25 of filling when the yarn has been woven off down to the preliminary winding, which contains sufficient yarn to last while the change is being made. Such spinning apparatus forms the subject matter of United 30 States Patents No. 680194 to Chapman; Nos. 686906, 722,145 and 798704 to Rhoades, and in all of these patents the bunch-like character of the preliminary winding is a feature, the bunch being formed with short and uniform 35 traverses and then the traverse is lengthened automatically for the main winding.

In my present invention I have departed very markedly from the structures and mode 40 of operation detailed in the patents referred to, and while the bobbins formed by my novel apparatus are also designed for use with feeler looms they possess certain characteristics which result in an improved operation in any loom, whether supplied with a feeler or not.

It has been found in practice that sometimes the "bunch" on a bunch-wound bobbin interposes an obstruction to the free 45 delivery of the yarn when the latter, in weaving off, has to draw off over the bunch, the obstruction tending to break the yarn. By means of my present invention I overcome this objection by a novel arrangement of the

traverse, and while the yarn laid at the very 55 beginning of the operation co-operates at the proper time with the feeler, in a feeler-loom, it does not comprise all the yarn which is laid by a shorter traverse than that employed for the main winding, and therefore it can 60 hardly be termed a "bunch" in the usual meaning of that word in the art; the yarn mass remaining when the feeler acts has less length, relatively to its thickness, than heretofore, and consequently there is a less quantity 65 of waste even should the setting of the feeler be imperfect.

The weaving off of the yarn from a bobbin produced in accordance with my present invention is not obstructed in the slightest 70 from the beginning to the end of the weaving off, and while there is a small portion of the yarn adapted to effect the proper operation of a feeler it offers no obstruction to the yarn as it is drawn off the bobbin. I am also enabled 75 by my invention to spin a greater quantity of yarn on a given bobbin, as will appear hereinafter.

The mechanism hereinafter to be described, as illustrating one practical embodiment of my invention, is very simple and composed of few parts, and it is readily applicable to the ordinary ring-spinning apparatus with slight expenditure of time and labor.

The operation of the mechanism is entirely automatic from start to finish in winding the yarn upon a bobbin.

The various novel features of my invention will be fully described in the subjoined 90 specification and particularly pointed out in the following claims.

Figure 1 is a front elevation of a portion of a spinning-frame having one embodiment of my present invention applied thereto, the parts being shown in readiness to begin the winding of a set of bobbins, the ring-rail being at its lowest point; Fig. 2 is a transverse sectional view on the line 2--2, Fig. 1, looking toward the left, the actuating cam for the builder-motion being partly broken out, and the builder-arm being at the bottom of its stroke; Fig. 3 is a detail in front elevation of part of the means whereby the rise of the ring-rail is controlled, the members shown 105 being in the position illustrated in Fig. 1; Fig. 4 is a view similar to Fig. 3, but showing the position assumed by the members when

the maximum traverse is attained; Fig. 5 is a top plan view of the parts shown in Figs. 3 and 4, and also showing the controlling device whereby the traverse of the ring-rail is gradually increased from minimum to maximum; Fig. 6 is a vertical sectional detail on the line 6—6, Fig. 5, to show more clearly a portion of the controlling device, to be referred to; Fig. 7 is a rear view of the segmental, angularly movable carrier and the guide thereon, illustrated in front elevation, Figs. 1, 3 and 4; Fig. 8 is a detail view of the drum shown by dotted lines in Fig. 1; Fig. 9 is a view in elevation of a bobbin with a small portion of yarn wound thereupon, shortly after the beginning of the winding operation; Fig. 10 is a similar view, broken out between top and bottom, of a full bobbin, showing the general shape thereof and the increased quantity of yarn upon the lower end; Fig. 11 is a sectional view of one half the yarn mass to better illustrate the manner in which the yarn is laid upon the yarn-receiver or bobbin.

In the present embodiment of my invention the ring-rail is raised by a suitable lifting-weight and depressed by or through means actuated by the builder-motion, the usual winding mechanism thereof letting off the chain from the barrel gradually to effect the "gain" of the traverse, as the yarn is laid upon the yarn-receiver. Ordinarily the gradual unwinding of the chain attached at one end to the barrel will cause the ring-rail to rise a little higher on each ascent, and at each descent to go not quite so low as on the previous descent, to lay the yarn in successive layers upon the bobbin from the base to the upper end thereof. Herein, however, I have modified the action of the winding mechanism, as to the gain of the traverse at both its upper and its lower end, as will be explained, whereby primarily the yarn is laid with a gradually increasing traverse, and the lower end or base of the yarn mass is con-45 vaxed or rounded, instead of upwardly tapered, thereby increasing the amount of yarn laid.

In Figs. 1 and 2 the spindle-rail 1, rotatable spindles 2, the vertically reciprocating ring-rail 3 provided with rings 4 for the spindles, the lifter-rods 5, only one being shown in Fig. 1, the rocker 6 coöperating with the foot of the lifter-rod and provided with a weight 7 to elevate the ring-rail, and the up-turned rocker-arm 8 rigidly connected with the rocker and transmitting reciprocating movement to the other lifter-rods through link 9, may be and are all substantially of well known or usual construction in spinning or similar apparatus. The rocker-arm 8 has the usual segment 10, Fig. 1, and herein I have shown a branch 11 adjustably connected with the rocker-arm, the branch having a portion embracing the arm and longitudinally slotted at 12 for a clamping bolt 13,

whereby the branch may be adjusted longitudinally of the arm, to vary the swing of the rocker-arm, as is usual.

The builder-motion herein shown includes a builder-arm 14 fulcrumed on the main frame at 15, Fig. 2, and provided with a roller or other stud 16 constituting a follower to coöperate with a single actuator, shown as a traverse-cam 17 having four points, the weight 18 connected with the builder-arm counterbalancing the weight of the parts mounted on the arm and acting to keep the follower 16 in engagement with the traverse cam. Said builder-arm has a constant stroke, as will be manifest, and upon the arm is mounted substantially usual winding mechanism, including a double-grooved barrel 19, pick-shaft 20 provided with a worm 21 to effect gradual rotation of the barrel, pick-wheel 22 on the shaft 20, an actuating-pawl 23 operated in usual manner, and a chain 24 wound around and attached to the barrel, the chain lying in one of the grooves of said barrel. The chain 24 is carried upward and secured to a rotatable drum supported in arms 25, 26, of a bracket or stand 27 bolted to one end of the main frame, above the builder-motion, as shown in Fig. 1, the bracket arms having extended through them a fulcrum rod 27^x on which the drum 28 is mounted to rotate, the said drum having a peripheral groove 29 formed by the end and center flanges 30, 31, and a disk 32 of considerably greater diameter than the drum is secured to or forms a part of it, the disk and the central flange 31 forming a second peripheral groove. The bottom of the groove 29 is cylindrical and the chain 24, which is attached to the drum within said groove gradually winds onto the drum, as it is let off, little by little, by the winding mechanism, in usual manner. The groove between the center flange and the disk 32, however, is in the present embodiment of my invention non-cylindrical, the bottom of the groove being slabbed off or flattened as at 33^x, clearly shown in Fig. 8, for a purpose to be hereinafter described. The disk 32 has extended from its front face a pin or stud 34 near its periphery, and between the disk and the bracket arm 26 is mounted a segmental carrier 35 having projecting from its inner face a guide shown as an elongated lug or ear 36, and the carrier is also provided with a roller or other stud 37, the guide and stud being very clearly shown in Fig. 7. The carrier has a hub or sheave 38 through which the fulcrum-rod 27^x extends, the carrier being thereby fulcrumed to swing about said rod and to move the guide 36 in a curved path above the drum and through an arc having a much greater radius than the radius of the drum. The controlling means whereby the angular movement of the carrier and its guide is gov-

125

130

erned will be hereinafter referred to in detail. The hub 38 is of sufficient length to extend up to the outer face of the disk 32, as best shown in Fig. 2.

5 A chain or other flexible member 39 is pivotally connected at one end to the stud 34, and is thence carried under the hub 38 and upwards over the roller or other stud 37 and the guide 36, and thence toward the branch 10 or arm 11 attached to the rocker arm 8, a connection between the flexible member 39 and said arm 11 being effected in the present embodiment of my invention by a longitudinally adjustable link 40, the two members 15 composing the link being connected by a turn-buckle or other suitable adjustable coupling 41, see Fig. 1. By lengthening or shortening the link, it will be manifest that the distance between the upper end of the 20 arm 11 and the nearer end of the flexible member 39 can be increased or decreased for a purpose to be hereinafter referred to. The upper surface of the guide 36 is convexed, as shown, and the member 39 rests upon such 25 convex surface.

Viewing Fig. 1, it will be seen that if the disk 32 is turned in the direction of the arrow 33, said member or chain 39 will be unwound more or less from around the hub 38, according to the extent of such angular movement 30 of the disk, the chain of course slackening during such movement, but to a very slight degree. The link 40, flexible member or chain 39, and the disk 32, form a connection between the ring-rail and the builder-motion. When the builder-arm 14 rises, the weight 7 will act to swing the rocker-arm 8 to the right, Fig. 1, to elevate the ring-rail, and through the connection just described, 35 the drum and disk will be turned more or less in the direction of the arrow 33, depending of course upon the amplitude of the stroke of the builder-arm. When the builder-arm descends, the drum and disk will be rotated 40 in a reverse direction to the arrow 33, and the chain 39 and link 40 will be tightened again, but owing to the "gain" due to the winding mechanism, said disk will not return the stud 34 to exactly the point shown 45 in Fig. 1, but such point will be advanced, though to a very slight degree, and as the operation continues, these slight advances will finally make a considerable change in the position of the parts when compared 50 with the position shown in Fig. 1, or in Fig. 3.

A second chain or flexible member 42 is attached at one end to the segmental head 10 of the rocker-arm 8, and is carried thence 55 around the drum between the center flange 31 and the disk 32, and thence passes over the flattened portion 33^X of the drum hereinbefore referred to, said chain and the drum forming a second connection between the builder-motion and the ring-rail, it being understood of course that the chain 24 is the

connecting member between the drum and the builder-motion. For a given angular movement of the disk and drum from the position shown in Fig. 1, due to oscillation of the builder-arm, it will be manifest that 70 the member or chain 42 will give off a greater amount than the member or chain 39 because of the difference in radii of the sheave or hub 38 and the drum, and consequently when the yarn winding operation 75 begins, the chain 42 will slacken slightly, as the ring-rail rises, so that the upper end of the stroke of the ring-rail is controlled by or through the chain 39, and on the descent of the ring-rail the lower end of its stroke will 80 be determined by the chain 42, as the latter tightens more quickly than the connection including the member 39, it being remembered that on the down-stroke of the ring-rail the disk and drum turn in the direction 85 opposite to the arrow 33, and on the up-stroke they turn in the direction of said arrow.

The bracket 27 is provided on its top with bridges 43, 44, to retain in place and also to 90 guide a cam-like controller 45, shown in plan in Fig. 5, as substantially triangular in shape, the rearward inclined edge 46 cooperating with a follower shown as an arm 47 longitudinally slotted at 48, see Fig. 7, 95 to receive the controller and extended forward and pivotally connected at 49 with the carrier 35, the outer end of the slot 48 being beveled as at 50 to engage the diagonal or inclined edge 46 of the controlling member 100 45. If the latter is held stationary, it will be manifest that the carrier can have no movement on its fulcrum 27^X, and consequently the guide 36 will be stationary. When, however, the controlling member 45 is moved in the direction of the arrow 51, 105 see Fig. 5, the follower 47 will be permitted to move to the right, viewing Figs. 1 and 5, and thereby the carrier 35 will gradually move the guide 36 and stud 37 from the position shown in Figs. 1 and 3 to that shown in Fig. 4. The movement of the controlling member 45 is effected intermittently and is controlled by or through the builder-motion.

Referring to Fig. 2, the straight extension 52 of the controlling member 45 is connected by a link 53 with the upper end of an arm 54 mounted on a fixed fulcrum 55, the end of the arm below the fulcrum being slotted longitudinally as at 56. An extension 57 is adjustably secured to the lower end of the arm by a clamping bolt 58 extended through the slot 56, the extension having connected with it one end of a link 59, the other end of the link having attached to it a short chain 60 which is wound around the barrel 19 of the winding mechanism in the second one of the grooves thereof, as shown in Fig. 1. As the winding mechanism lets off the chain 24 little by little, it also 110 120 125 130

lets off the chain 60, and consequently the controlling member 45 is moved to the left, viewing Fig. 2, owing to the pull exerted on the follower 47 transmitted from the rocker-arm through the carrier 35. Remembering that the lower end of each stroke of the ring-rail is determined by the connection 42, and that the upper end of each stroke is determined by or through the link 40 and chain 39, it will be manifest that as the winding mechanism operates, the "gain" due to the unwinding of the chain 24 from the barrel 19 will cause the ring-rail to descend, not quite so low as it did on the previous stroke, and as the stud 34 is gradually advanced by or through the action of the winding mechanism of the builder-motion the ring-rail will rise a little higher on each up-stroke. It is desired, however, to wind a portion of the bobbin with a traverse gradually increasing from the minimum traverse to the maximum, and this increase of the traverse is effected by the gradual and intermittent movement of the guide 36 to the right Fig. 1, as the cam-like controlling member 45 is gradually moved in the direction of the arrow 51, Figs. 2 and 5. This controlling device is governed by the builder-motion, as has been described, and it causes the ring-rail to ascend a greater distance on each up-stroke than the "gain" at the lower end of each stroke, the latter being due to the action of the builder-motion and winding mechanism thereof conveyed through the chain 42. Hence the traverse gradually increases until, owing to the gradual advance of the segmental carrier 35 and the disk 32, more slack is given to the flexible member 39 on the up-stroke of the builder-arm than is given to the chain or connection 42, and at this point in the operation the position of the parts is shown in Fig. 4, when the maximum traverse has been attained. The advance movement of the segmental carrier 35 continues thereafter until the edge 50 of the follower 47 moves off the diagonal face 46 of the controlling member, maintaining the connection 39 slack while the connection 42 operates. When the maximum traverse is attained the chain or connection 42 then assumes entire control of the ring-rail and governs the rise of the latter as well as the descent on each stroke, and the traverse will consequently be uniform, as the winding mechanism provides for a uniform gain.

If the surface of the drum 28 around which the flexible member 42 passes were completely cylindrical, the gain at the bottom of each traverse would be uniform from the beginning to the end of the operation of winding the yarn upon a yarn-receiver or bobbin, but the flattening of a portion of the periphery of the drum, as at 33^x, causes a variation in such gain. So long as the member 42 draws across the flattened portion 33^x,

the gain at the lower end of the traverse at the start is very minute, but it will be slowly and gradually increased as the drum advances and hence the mass of yarn at the base of the bobbin will be built out or rounded as at 61, Figs. 9, 10 and 11, up to the point where the yarn is laid with a second or uniform traverse. By this time the drum has advanced to the position shown in Fig. 4, so that from that point to the end of the operation, the member 42 draws off from a cylindrical part of the drum; and hence the gain is at its maximum and due entirely to the builder-motion and is uniform for each traverse. The amount of yarn added to the yarn mass on the bobbin by this arrangement is shown in Fig. 10, as without it the lower portion of the bobbin would be shaped as indicated by the divergent dotted lines 62.

In Fig. 11, I have endeavored to indicate the successive layers or windings of yarn, first with a gradually increasing traverse up to a maximum, and thereafter with the maximum traverse, and it will be seen by reference to that figure, and also to Fig. 9, that while there is an initial winding as 63 on the bobbin, it does not partake of the characteristics of the so-called "bunches" wound by bunch-building mechanism, which I have hereinbefore referred to, since the "bunches" are built up with a uniform traverse, while my initial winding is built up with an increasing traverse beginning with a very small traverse. The initial winding, however, is amply sufficient to effect the proper operation of the feeler in a feeler loom, to change filling prior to complete exhaustion of the running filling. As a matter of fact with a bobbin wound by the mechanism embodying my present invention, there is considerably less yarn in the remaining mass at the time the feeler acts, relatively to the thickness of the yarn mass than in the bunches heretofore wound, and consequently a less amount of yarn left on the bobbin when a change of filling is effected, even should the feeler be set improperly or inexactly.

In order that the upper portion of the primary winding of yarn upon the bobbin shall contain a proper amount of yarn it is necessary to make a change in the speed of the ring-rail at the upper part of each traverse while the winding is proceeding with a gradually increasing traverse. That is, by effecting the control of the ring-rail at the upper part of the traverse during such winding by or through the connection 39 the speed of the rail is diminished at the upper part of each stroke and as the rail moves more slowly a greater quantity of yarn is laid. Should the upper part of the traverse be controlled by the connection 42 during the period of gradually increasing traverse the speed of the rail would be greater and

less yarn would be laid, so that the primary winding would be pear-shaped or like an inverted top, tapering too quickly from the base upward. The stroke of the ring-rail, 5 whether longer or shorter, must always be effected in the same time as the builder-arm has a constant stroke and effects the operation of both the connections between the said arm and rail.

10 A certain fixed amount of yarn must be laid on the bobbin at each traverse and a shorter traverse lays a greater number of layers of yarn than a longer traverse does, but by the relatively rapid increase in the 15 traverse during the primary winding I obviate improper laying up of the yarn on itself and by reducing at such time the speed at the upper part of the traverse I lay more yarn than would otherwise be laid, obviating 20 the pear-shaped form above referred to.

In order to adjust the length of the minimum traverse, the link 40 is lengthened or shortened, in order to thereby permit the member 42 to begin its work a little sooner 25 or a little later. By lengthening the link 40, the length of the minimum traverse will be increased, and it will be decreased by shortening the link, but it will be understood that these changes in the length of the minimum 30 traverse are comparatively very slight. The more rapidly the carrier 35 is moved from starting position, Fig. 1, to final position Fig. 4, the quicker will be completed the winding of yarn with the gradually increasing traverse, and the adjustment of the part 57 on 35 the lower end of the arm 54 provides for such variation. If the said extension 57 is moved downward from the position shown in Fig. 2, the distance from the fulcrum 55 to the link 40 59 will be increased, and therefore the movement of the cam or controlling member 45 will be slower, whereas if the extension 57 is moved upward to bring the link 59 nearer the fulcrum 55, the movement of the controlling 45 member 45 will be hastened and consequently the winding with a gradually increasing traverse will be shortened.

The oscillation of the builder-arm has no particular effect on the arm 54, as the point 50 of connection between the link 59 and said arm is so near that of the fulcrum 15 on which the builder-arm oscillates.

The novel mechanism herein set forth is very simple in its structure, and is very 55 readily applied to a spinning frame of usual construction, for it will be seen that the bracket 27 carries everything requisite to form the bobbin, first with a gradually increasing traverse, and thereafter with a uniform 60 form or constant traverse, with the exception of the arm 54.

When the member 42 has sole control of the ring-rail, as when the yarn is being laid with a constant traverse, the continued advance 65 of the segmental carrier 35 and the

disk 32 slackens or eases off the flexible member or chain 39, keeping pace with or exceeding the gain due to the winding mechanism transmitted through the member 42, for as soon as said member 42 assumes complete 70 control of the ring-rail, the other connection between the ring-rail and the builder-motion becomes inoperative to exert any control upon the ring-rail. A lug 35* on the outer face of the segmental carrier 35 is adapted 75 to bear against the bracket-arm 26 when the carrier is in its extreme advanced position, to at such time relieve the straight extension 52 of the controlling member 45 from any further strain due to the pull through the chain and 80 link 39 and 40. After the full yarn load has been laid upon a set of bobbins and the frame is doffed, the winding mechanism is wound down in usual manner, and thereby the two connections between the ring-rail 85 and the builder-motion are restored to the position shown in Fig. 1, in readiness for the winding of a fresh set of bobbins.

During the formation of the primary winding of yarn, the builder-motion acts upon the 90 ring-rail first through one connection and then through the other, in alternation, to control the upper and lower ends of the traverse respectively, as has been described, and when the maximum traverse has been 95 attained, one of the connections becomes inoperative automatically, and the other connection completes the secondary winding with a constant traverse.

My invention is not restricted to the precise construction and arrangement herein shown and described, as the same may be modified or rearranged in various particulars by those skilled in the art without departing from the spirit and scope of my invention. 100

Having fully described my invention, what I claim as new and desire to secure by Letters Patent is:—

1. In apparatus of the class described, a builder-motion, including a builder-arm having a constant stroke, a reciprocating ring-rail, and connections between it and the builder-arm, including means to effect reciprocation of the ring-rail with a gradually increasing traverse to a predetermined maximum, and thereafter to continue automatically the reciprocation of the ring-rail with a uniform traverse, said connections including means to reduce the speed of the ring-rail at the upper part of its stroke during the period 115 of gradually increasing traverse.

2. In apparatus of the class described, a builder-motion, including a builder-arm having a constant stroke, a reciprocating ring-rail, separate connections between said ring rail and the builder-arm, each connection being operated directly by the latter, one connection including means to effect a uniform 125 traverse of the ring-rail, the other connection including means to effect a gradually in- 130

creasing traverse of the ring-rail to a predetermined maximum, and a controller to govern automatically the rate of increase in the traverse due to the second-named means.

5. 3. In apparatus of the class described, a builder-motion, including a builder-arm having a constant stroke, means mounted independently of said arm but actuated thereby to effect automatically the formation of a 10 primary winding with a gradually increasing traverse, and thereafter a secondary winding with a uniform traverse, of yarn upon a yarn-receiver, said means including an instrumentality to reduce the speed of the traverse at 15 the upper portion of the stroke during the period of primary winding.

4. In apparatus of the class described, a builder-motion, including an oscillating member having a constant stroke, and separate 20 means each actuated directly by said member to effect through the builder-motion the automatic formation of a primary winding with a traverse gradually increasing from minimum to maximum, and a secondary 25 winding with the maximum traverse, of yarn upon a yarn-receiver.

5. In apparatus of the class described, a builder-motion, including an oscillating member, a single actuating device to impart a 30 constant stroke thereto, and means actuated by and mounted independently of the said member to effect automatically the formation of two successive windings of yarn upon a yarn-receiver, the first winding being laid 35 with a gradually increasing traverse, said means including an instrumentality to intermittently assume control of and reduce the speed of the traverse during the first winding specified.

40. 6. In apparatus of the class described, a builder-motion, including an oscillating member having a constant stroke, to lay yarn with a long and uniform traverse upon a yarn-receiver, combined with separate means 45 actuated directly by said member to effect, when operative, a winding of yarn upon the yarn-receiver with a traverse gradually increasing in length to that of the uniform traverse referred to and reducing the speed 50 of the traverse at the upper portion thereof.

7. In apparatus of the class described, a builder-motion, including an oscillating member having a constant stroke, and means actuated by said member to effect automatically the formation of two successive 55 windings of yarns upon a yarn-receiver, the first winding with a gradually increasing traverse, combined with separate means to automatically determine the rate of such increase.

8. In apparatus of the class described, a builder-motion, including an oscillating member having a constant stroke, and means actuated by said member to effect auto-

matically the formation of two successive 65 windings of yarn upon a yarn-receiver, the first winding with a gradually increasing traverse, combined with a cam to determine automatically the rate of such increase, and separate means to govern the movement of 70 the cam by or through the builder-motion.

9. In apparatus of the class described, a builder-motion, including an oscillating member having a constant stroke, and means actuated by said member to effect automatically the formation of two successive windings of yarn upon a yarn-receiver, the first winding with a gradually increasing traverse, combined with a cam to determine automatically the rate of such increase, and 80 manually adjustable means to vary the movement of the cam by or through the builder-motion.

10. In apparatus of the class described, a builder-motion, including an oscillating member having a constant stroke, and means actuated by said member to effect automatically the formation of two successive windings of yarn upon a yarn-receiver, the first winding with a gradually increasing 85 traverse, combined with means to determine automatically the rate of such increase, and manually operated separate means to determine the length of the minimum traverse.

11. In apparatus of the class described, a 90 builder-motion, including an oscillating member having a constant stroke, and means actuated by said member to effect automatically the formation of two successive windings of yarn upon a yarn-receiver, the first winding with a gradually increasing 95 traverse, combined with separate means governed by or through the builder-motion to control the rate of such increase, and separate, manually adjustable means to regulate 100 the length of the minimum traverse.

12. In apparatus of the class described, a builder-motion, including an oscillating member having a constant stroke, and means actuated by said member to effect automatically the formation of two successive windings of yarn upon a yarn-receiver, the first winding with a gradually increasing traverse, combined with a cam to determine automatically the rate of such increase, adjustable connections between the builder-motion and the cam to effect operative movement of the latter, and independent means to fix the minimum length of traverse.

13. In apparatus of the class described, a 120 builder-motion, including an oscillating member having a constant stroke, and means actuated by said member to effect automatically the formation of two successive windings of yarn upon a yarn-receiver, the first 125 winding with a gradually increasing traverse, combined with a movable member the movement whereof is controlled separately by the

builder-motion, to govern the increase of traverse, and adjustable means to regulate the length of the minimum traverse.

14. The combination, with a reciprocating ring-rail and a builder-motion including a builder-arm having a constant stroke, of separate connections between the builder-motion and the ring-rail to control the movement of the latter, one of said connections including a constant traverse instrumentality, and a traverse increasing instrumentality included in the other connection, to effect a primary winding of yarn on a yarn-receiver by or through said latter connection and thereafter to effect a secondary winding by or through the first connection, both of said connections and the instrumentalities included therein being actuated by the builder-arm.
20. 15. The combination, with a reciprocating ring-rail, a builder-motion including a builder-arm, and an actuating cam to impart a constant stroke to said arm, of separate connections between the latter and the ring-rail, to control the movement of the latter, both connections being operated directly by the builder-arm, and means actuated by the builder-arm to act through said connections and impart a traverse gradually increasing from minimum to maximum, and thereafter a uniform traverse to the ring-rail.

16. The combination, with a reciprocating ring-rail, and a builder-motion, of separate connections between it and the ring-rail, to control the movement of the latter, means actuated by the builder-motion to act through said connections to impart primarily a gradually increasing traverse, and thereafter a uniform traverse, to the ring-rail, and means to govern automatically the rate at which the primary traverse increases.

17. In apparatus of the class described, a builder-motion, means actuated thereby to effect automatically the winding of yarn upon a yarn-receiver with a gradually increasing traverse to a predetermined maximum, and thereafter to complete the winding with such maximum traverse, and means to reduce the speed of the traverse at the upper part thereof during the period of gradually increasing traverse.

18. In apparatus of the class described, means to effect the winding of yarn upon a yarn-receiver with a traverse gradually increasing from minimum to maximum, separate means to thereafter complete automatically the winding with the maximum traverse, and a common actuator for the said means.

60 19. In apparatus of the class described, a builder-motion, means actuated thereby to effect the winding of yarn upon a yarn receiver with a traverse gradually and uniformly increasing from minimum to maxi-

num, means to complete the winding with such maximum traverse, also actuated by the builder-motion, and a separate instrumentality to effect automatically the change from increasing traverse to constant traverse.

20. In apparatus of the class described, a builder-motion, two winding means actuated thereby to respectively wind yarn on a yarn-receiver with a gradually increasing traverse up to a predetermined traverse, and thereafter to continue and complete the winding with a constant traverse, and an instrumentality controlled by the builder-motion to govern the increase of traverse when the first-named means is operating.

21. In apparatus of the class described, a reciprocating ring-rail, a builder-motion, means actuated thereby to govern temporarily the rise of the ring-rail and impart thereto a gradually increasing upward stroke, separate means actuated by the builder-motion to effect the descent of the ring-rail and cause the low point of its stroke to rise gradually but to a less extent than the increase in its upward stroke, to thereby wind yarn upon a yarn-receiver with a gradually lengthening traverse to a maximum, and connections between the ring-rail and both of said means, the connection between the first-named means and the ring-rail becoming inoperative when the maximum traverse is attained, the second means thereafter solely controlling the reciprocation of the ring-rail and completing the winding with the maximum traverse.

22. The combination, with a reciprocating ring-rail, and a builder-motion, of means actuated thereby to govern the descent of the ring-rail throughout the winding of yarn upon a yarn-receiver, to thereby determine one end of each traverse, separate means also actuated by the builder-motion to govern the rise of the ring-rail for a portion of the winding, to thereby determine the other end of each traverse while such means is operative, and a controlling device for said latter means, to impart a gradual increase in the length of the traverse during the operation of the said means, the first named means thereafter controlling the rise as well as the descent of the ring-rail, whereby a primary winding of yarn is laid with a constantly increasing traverse and a secondary winding with a constant traverse throughout such secondary winding.

23. The combination, with a reciprocating ring-rail, and a builder-motion, of means actuated thereby to govern the descent of the ring-rail throughout the winding of yarn upon a yarn-receiver, to thereby determine the lower end of each traverse, said means including a member to increase the gain at the lower end of the traverse after a predetermined winding of yarn, separate means governed by the builder-motion to govern the

rise of the ring-rail for a portion of the winding and impart to each traverse a gradually increasing gain at the upper end thereof while such means is operative, the first-named 5 means automatically assuming entire control of the ring-rail thereafter and completing the winding with the maximum traverse.

24. The combination, with a reciprocating ring-rail, and a builder-motion, including a 10 builder-arm and a winding mechanism thereon, of a rotatable drum operatively connected with said arm, a flexible member between the ring rail and drum and adapted to unwind from the latter, a sheave co-axial with and of 15 less diameter than the drum, a disk of greater diameter than and rotatable with the drum, a co-axially fulcrumed carrier having a guide thereon movable in a segmental path above the drum, a connection between the ring- 20 rail and disk, including a flexible member attached to the disk near its periphery and passed under the sheave and upward to the guide and thence extended toward the point of connection with the ring-rail, and means 25 to effect automatically intermittent angular movement of the carrier to gradually advance the guide.

25. The combination, with a reciprocating ring-rail, of means to control and determine 30 the lower end of each stroke thereof, separate means to control and determine the upper end of each stroke of the ring-rail and impart a gradually increasing traverse thereto, and a builder-motion to effect the actuation 35 of each of said means, said builder-motion including a winding mechanism to cause the gain at the lower end of the traverse of the ring-rail.

26. The combination, with a reciprocating 40 ring-rail, of means to control the descent thereof and determine the lower end of each stroke, separate means to control the rise of the ring-rail, a governing device for said means, to impart automatically a gradually 45 increasing traverse to the ring-rail, and a builder-motion to actuate each of said means and also controlling the governing device, said builder-motion including a winding mechanism to cause the gain at the lower end 50 of the traverse of the ring-rail, the gain at the upper end of the traverse due to the governing device being greater than the gain at the lower end.

27. The combination, with a reciprocating 55 ring-rail, and a builder-motion including a winding mechanism, of means to determine the lower end of each stroke of the ring-rail, the winding mechanism imparting the gain thereto, a device to modify the action of said 60 mechanism and increase the gain during the first part of the winding, separate means to control the upward stroke of the ring-rail and gradually increase the gain thereto to impart an increasing traverse during the first part of 65 the winding, and a device to render said lat-

ter means inoperative when the first part of the winding is completed, the means theretofore determining the lower end only of the stroke then assuming complete control of the ring-rail and maintaining such control during the balance of the winding.

28. The combination, with a reciprocating ring-rail, and a builder-motion, of separate means actuated by the builder-motion to jointly control the ring-rail and impart thereto a gradually increasing traverse, to lay a primary winding of yarn upon a yarn-receiver, and mechanism to automatically render inoperative one of said means at a predetermined time, the other of said means continuing in operation and altogether controlling the ring-rail, imparting a constant traverse thereto and forming a secondary winding of yarn upon the yarn-receiver.

29. The combination, with a reciprocating ring-rail, and a builder-motion, including a 85 builder-arm having a constant stroke, of two separate connections between said arm and the ring-rail, to control the traverse thereof, each connection including a member 90 oscillated by the arm and also gradually advanced angularly, said members having different radii, whereby for a predetermined period one connection controls the descent and the other connection the rise of the ring-rail, and means acting through the latter connection to gradually increase the traverse to a predetermined maximum, and thereafter to render said connection inoperative, the other connection thereupon automatically 100 assuming complete control of the ring-rail and imparting thereto a constant traverse.

30. The combination with a reciprocating ring-rail, and a builder-motion including a builder-arm having a constant stroke, of 105 two separate connections between said arm and the ring-rail, to control the traverse thereof, each connection including a member oscillated by the arm and also gradually advanced angularly, said members having different radii, whereby one connection controls the descent and the other connection the rise of the ring-rail, and means acting through the latter connection to gradually increase the rising stroke of the ring-rail a 110 greater amount than the gain at the lower end of the stroke, to thereby impart a gradually increasing traverse to the ring-rail.

31. The combination, with a reciprocating ring-rail, and a builder-motion including a 120 builder-arm having a constant stroke, of a connection between the arm and the ring-rail, including means to govern the descent of the ring-rail and gradually raise the low point to which it descends, a second connection between the builder-arm and the ring-rail including means to govern the rise of the ring-rail and gradually raise the high point to which it ascends, and a controlling device 125 acting through the second connection to aug- 130

ment the gain on the rise of the ring-rail, whereby a gradually increasing traverse is imparted thereto.

32. In apparatus of the class described, means to effect the winding of yarn upon a yarn-receiver with a traverse gradually increasing from minimum to maximum, separate means to thereafter complete automatically the winding with the maximum traverse, and a common actuator for both said means, the second-named means including a device to gradually increase the gain at the lower end of the traverse during the winding with a gradually increasing traverse.

33. The combination, with a reciprocating ring-rail, and a builder-motion including an oscillating member having a constant stroke, of means actuated by said member to govern the reciprocation of the ring-rail and effect the winding of yarn upon a yarn-receiver with a traverse gradually increasing from minimum to maximum, and separate means also actuated by said oscillating member and also governing reciprocation of the ring-rail

to thereafter complete automatically the winding with the maximum traverse, the latter means including a device to gradually increase the gain at the lower end of the traverse during the first mentioned winding.

34. The combination, with a reciprocating ring-rail, and a builder-motion, including a builder-arm and a winding mechanism thereon, of mechanism actuated by the builder-motion to govern the reciprocation of the ring-rail, including a drum having a portion of its periphery flattened, and a flexible connection wound around the drum, to gradually increase the gain at the lower end of the traverse while the flexible connection draws across the flattened portion of the drum.

In testimony whereof, I have signed my name to this specification, in the presence of two subscribing witnesses:

JONAS NORTHRUP.

Correction in Letters Patent No. 882,793.

It is hereby certified that in Letters Patent No. 882,793, granted March 24, 1908, upon the application of Jonas Northrop, of Hopedale, Massachusetts, for an improvement in "Traverse-Motion for Yarn-Spinning Apparatus," an error appears in the printed specification requiring correction, as follows: In line 93, page 6, the word *separate* should be stricken out and inserted before the word "means" in line 91, same page; and that the said Letters Patent should be read with this correction therein that the same may conform to the record of the case in the Patent Office.

Signed and sealed this 14th day of April, A. D., 1908.

C. C. BILLINGS,
Acting Commissioner of Patents.

ment the gain on the rise of the ring-rail, whereby a gradually increasing traverse is imparted thereto.

32. In apparatus of the class described, means to effect the winding of yarn upon a yarn-receiver with a traverse gradually increasing from minimum to maximum, separate means to thereafter complete automatically the winding with the maximum traverse, and a common actuator for both said means, the second-named means including a device to gradually increase the gain at the lower end of the traverse during the winding with a gradually increasing traverse.

33. The combination, with a reciprocating ring-rail, and a builder-motion including an oscillating member having a constant stroke, of means actuated by said member to govern the reciprocation of the ring-rail and effect the winding of yarn upon a yarn-receiver with a traverse gradually increasing from minimum to maximum, and separate means also actuated by said oscillating member and also governing reciprocation of the ring-rail

to thereafter complete automatically the winding with the maximum traverse, the latter means including a device to gradually increase the gain at the lower end of the traverse during the first mentioned winding.

34. The combination, with a reciprocating ring-rail, and a builder-motion, including a builder-arm and a winding mechanism thereon, of mechanism actuated by the builder-motion to govern the reciprocation of the ring-rail, including a drum having a portion of its periphery flattened, and a flexible connection wound around the drum, to gradually increase the gain at the lower end of the traverse while the flexible connection draws across the flattened portion of the drum.
